JOSEPH C. HARVEY, OF CHICAGO, ILLINOIS, ASSIGNOR TO JOHN THOMAS UNDERWOOD,
OF BROOKLYN, NEW YORK.

TYPE-WRITING MACHINE.

1,169,400.

Specification of Letters Patent. Patented Jan. 25, 1916.

Application filed February 1, 1913. Serial No. 745,573.

To all whom it may concern:

Be it known that I, JOSEPH C. HARVEY, a citizen of the United States, residing in Chicago, in the county of Cook and State of Illinois, have invented certain new and useful Improvements in Type-Writing Machines, of which the following is a specification.

This invention relates principally to devices for making typewritten records, on "tally strips," of entries on bills and the like.

It has been the custom in some instances to superpose a tally strip upon a bill, in such position that the amounts appearing in the right-hand columns on the bill are also typewritten on the tally strip. The types strike through the ribbon directly upon both the bill and the strip. The body of the bill shows inked typewritten impressions, while the amounts are typewritten in ink on the tally strip, and with carbon impressions in the right-hand column of the bill. This is an objection, as it is desired that the amounts on the bill should also appear in ink.

One of the principal features of my improvements is to provide simple, inexpensive and readily applied means, whereby the entire bill may be typewritten with ink or may show ink-ribbon impressions, while a suitable record is made upon the tally strip.

To this end, I employ a tally strip which is made of transparent or translucent paper, and around the platen I place a band of carbon paper with the carbon side exposed. The tally strip is superposed upon the band, and the bill is superposed on the tally strip. The type impressions are therefore made on the underside of the tally strip, but this difficulty is overcome by making the tally strip of translucent paper, so that the typewritten matter may be read by looking through the sheet, the figures thus appearing in their natural shape and order.

The tally strip itself is illustrated as mounted on spools, which are carried upon a frame that is attached to the sheet-positioning tablet which is commonly used upon the platen frame of an Underwood type-writing machine. The spools may be arranged between the ends of the tablet, so that the tally strip may take a record of amounts written in columns at the middle of the bill or document; but of course the spools may be placed in other positions, as

for instance, at the right-hand end of the tablet, so as to take numbers written in the right-hand columns on the bill or worksheet.

Other features and advantages will hereinafter appear.

In the accompanying drawings, Figure 1 is a perspective front view of the platen carriage of an Underwood typewriting machine, showing my improvements applied thereto. Fig. 2 is a diagrammatic view showing the carbon band upon the platen, and illustrating the appearance of the reversed letters written on the underside of the tally strip. Fig. 3 is a view of one form of carbon band for the cylindrical platen. Fig. 4 is a side elevation to illustrate the friction-gear connection between the tally-strip spools. Fig. 5 is a sectional side elevation of the various devices.

Said Underwood machine usually comprises a cylindrical platen 1, revolvably mounted by means of an axle 2 in a platen frame 3. Feeding rolls 4 are usually provided; but in this case the rolls may (as illustrated) be omitted at the portion of the platen which is occupied by the tally strip, to avoid smutting the tally strip.

The platen is surrounded by a band 5 of carbon paper, which closely hugs the platen, and may be formed in one way by overlapping the ends of a strip as at 6 (Fig. 3), and joining the overlapping ends in any suitable manner, as by paste or mucilage. This makes practically an uninterrupted band, which, if a durable carbon is used, will yield a very large number of copies, and in fact may outlast several tally-strip rolls. If desired, a complete band may be pasted to the surface of the platen.

The tally strip 7, made of translucent paper, extends from a delivery spool 8 to a winding spool 9; the strip extending from one spool down to and around the platen and up to the other spool, and being carried beneath a guide rod 10, which extends along the platen and is fixed at its ends to the platen frame. It will be seen at Fig. 5 that this rod is back of the platen and beneath the spools, and that the tally strip is hence caused to grip the platen from the rear side thereof to the top, and to extend backwardly from the top around said guide rod 10; thus giving the tally strip so much grip upon the platen that the latter will drive the strip; 110

preferably no feed rolls 4 being employed at this point.

In the operation of the machine, the band 5 is placed around the platen. The strip 5 may be cut the proper length and wrapped around the platen, and its edges secured at 6 to make a complete band. Then the tally strip is led from delivery spool 8 and inserted at the rear side of the platen and carried around the same and up in front thereof and back under the rod 10, and then up to the winding spool 9. Then the bill or work-sheet 11 is inserted, and its front and side edges positioned by means of the usual sheet-positioning tablet 12; and then the feeding rolls 4 are set against the platen, and the typewriting operation proceeds in the usual manner, the type striking through the usual ribbon 13 against the front of the platen 1 or the work thereon. The bill or work-sheet 20 11 may extend on each side of the tally strip, as seen at Fig. 1, so that the strip will take off only the amounts that are entered down the side of that portion of the bill, but other 25 relative arrangements or dispositions of the bill and the tally strip may be adopted. As the writing proceeds line by line, the tally strip winds up on the spool 9, and the type-written impressions are made in ink on the 30 work-sheet 11, and in corresponding places are made in carbon on the back of the tally strip 7, as at Fig. 2; these impressions being made in reversed or unnatural positions, but being easily read from the front side of the 35 tally strip, owing to the translucent character thereof.

The delivery spool 8 is rotated by means of the pull of the revolving platen upon the tally strip 7; and a gear 14 connected to said 40 spool drives a pinion 15 connected to the winding spool 9; a friction washer 16 being interposed, however, between the pinion 15 and the spool 9, so as to permit the pinion 15 to slip; said pinion being preferably of 45 smaller diameter than the gear 14, and the friction washer 16 permitting the pinion 15 to turn considerably faster than the winding spool, whereby the tally strip is kept taut, but without danger of breaking the 50 strip; as there is only a light tension thereon. These spools are mounted upon a pair of brackets 17 secured by screws 18 to the underside of the tablet 12; and the latter may be adjusted along the rod 10, together with

the tally strip devices, and secured either 55 by set screws 19 or in the ordinary manner.

Variations may be resorted to within the scope of the invention, and portions of the improvements may be used without others.

Having thus described my invention, I 60 claim:

1. The combination with a platen, a platen frame and a sheet-positioning tablet mounted on said frame and adjustable along the delivery portion of the platen, of a mount 65 secured to said tablet, and a tally strip spool carried on said mount; whereby said mount and spool are adjustable along the platen together with said sheet-positioning tablet.

2. The combination with a platen frame 70 and a rotary platen mounted thereon, said frame comprising a paper shelf behind the platen, of a sheet-positioning tablet supported on the frame at the delivery side of and above the platen, in position to gage the 75 leading edge of a work-sheet extending around the platen and over the printing point, a mount secured to said tablet, and a tally strip spool carried on said mount, whereby said tablet and spool are adjustable 80 together lengthwise of the platen in a single operation.

3. The combination with a platen frame and a rotary platen mounted thereon, said frame comprising a paper shelf behind the 85 platen, of a sheet-positioning tablet supported on the frame at the delivery side of and above the platen, in position to gage the leading edge of a work-sheet extending 90 around the platen and over the printing point, a mount secured to said tablet, and tally strip receiving and supply spools carried on said mount, said tablet and mount adjustable together in a single operation along the platen to adjust the tally strip to 95 different positions along the platen.

4. A typewriter combining a platen, a sheet-positioning tablet above the platen to coöperate with a work-sheet at the delivery side of the platen, a mount secured to the 100 tablet, and a tally strip spool carried on said mount, said tablet and spool being adjustable together in a single operation along the platen in a letter-spacing direction.

JOSEPH C. HARVEY.
